Primary Examiner — Melanie H Tung(74) Attorney, Agent, or Firm — Sterne, Kessler, Goldstein & Fox PLLC(57) CLAIM

The ornamental design for a display screen or portion thereof with graphical user interface, as shown and described.

DESCRIPTION

The FIGURE is a front view of a display screen or portion thereof with graphical user interface showing my new design. The dashed line showing of the portion of a display screen, graphical elements, text and numbers form no part of the claimed design.
